COMPOUND JACK

Cecil F. Davey, Los Angeles, Calif.

Application March 29, 1938, Serial No. 198,657

4 Claims. (Cl. 254—102)

This invention relates to a compound jack of the type embodying a plurality of telescopic sections with screw means for advancing and retracting said sections relative to each other and 5 an arrangement whereby movement of one of the sections will be compounded relative to the movement of another of the sections.

An object of the present invention is to provide a construction in a compound jack of the above 10 character in which the telescopic sections are so arranged that the lowermost section will be innermost and the upper section will be outermost whereby when the several sections are disposed in their collapsed position the upper section will 15 serve as a housing for its associated inner and lower sections.

Another object is to provide a compound jack embodying telescopic sections together with an 20 arrangement of worm gears meshing with screw threads on said sections in which the worm gears and the screw threads engaged thereby are maintained completely housed interiorly of the jack 25 irrespective of the relative positions of the telescoped sections, so that the wearing surfaces of 30 the gears and threads will be protected against dust and grit, and whereby the exterior of the jack may be readily kept free of lubricating oils or grease.

With the foregoing objects in view, together 35 with such other objects and advantages as may subsequently appear, the invention is carried into effect as illustrated by way of example in the accompanying drawings, in which:

Fig. 1 is a view of the jack in elevation partly 40 in section showing it in its collapsed position;

Fig. 2 is a view in horizontal section taken on the line 2—2 of Fig. 1;

Fig. 3 is a view in horizontal section taken on the line 3—3 of Fig. 1;

Fig. 4 is a detail in horizontal section taken on the line 4—4 of Fig. 1;

Fig. 5 is a view in horizontal section taken on the line 5—5 of Fig. 1;

Fig. 6 is a view in section as seen on the line 45 6—6 of Fig. 1;

Fig. 7 is a view in vertical section, with parts in elevation, of the jack showing the telescopic sections thereof in a partly extended position relative to each other;

Fig. 8 is a detail in a horizontal section taken on the line 8—8 of Fig. 7;

Fig. 9 is a view in horizontal section taken on the line 9—9 of Fig. 7;

Fig. 10 is a view in elevation depicting a modified form of the invention in which the upper

outer section of the jack is fitted with an adjustable engaging bracket;

Fig. 11 is a plan view of the structure shown in Fig. 10.

Referring to the drawings more specifically, A 5 indicates generally the base of the jack which may be of any suitable construction but is here shown as embodying a housing having a top wall 14 and side wall 15. Erected on the base A is a tubular standard B having a base flange 16 secured to the wall 14 by bolts 17. Extending vertically through the standard is a tubular shaft 18 the bore of which is rectangular in cross section. The upper end portion of the shaft 18 projects above the standard and is fitted with a 15 worm wheel 19 and interposed between the worm wheel and the upper end of the standard is an end-thrust bearing 20. The lower end portion of the shaft 18 extends through the wall 14 into the interior of the base A and is fitted with a 20 bevel gear 21 which meshes with a companion gear 22 on a drive shaft 23 which extends through a bearing 24 in one of the side walls 15 and is fitted with a flattened end portion 25 for connection with a suitable driving means, such as a hand 25 crank or power driven shaft (not shown).

Encircling the standard B is a vertically movable sleeve C having internal threads 26 engaged by the worm gear 19 and which sleeve C is splined to the standard B by keys 27 mounted on the 30 inner lower end portion of the sleeve and which are slidably engaged with vertically extending channels or key-ways 28 extending longitudinally of the standard B.

Mounted in the rectangular bore of the shaft 35 18 is a shaft 29 of rectangular cross section which slidably fits the bore, and the upper end of which shaft projects above the upper end of the sleeve C and is fitted with a worm gear 30 having an external diameter exceeding that of the sleeve. 40 End thrust bearings 31 are interposed between the worm gear and the upper end of the sleeve C.

Encircling the sleeve C in telescopic relation thereto is an upper outer sleeve D formed with internal threads 32 which mesh with the worm 45 gear 30. The sleeve D is splined on the sleeve C by keys 33 mounted on the upper end portion of the sleeve C which slidably engage key-ways 34 extending longitudinally of the sleeve D on the interior thereof. The upper end of the sleeve D 50 is closed by a demountable end cap 35.

In assembling the jack the standard B is affixed to the base A by means of the bolts 17, whereupon the sleeve C is telescoped over the standard B by passing it downwardly over the 55

upper end of the latter with the keys 27 in place on the sleeve C and engaged with the key-ways 28. The sleeve C is of a length greater than that of the standard B so that when disposed in its 5 lowermost position relative to the latter the upper end portion of the sleeve C will project a short distance above the upper end of the standard. The bearing assembly 20 is then seated on the upper end of the standard B and the tubular shaft 18, preferably with the gear 21 affixed to the lower end thereof, is put in place by passing the shaft upwardly through the lower end of the standard B.

The shaft 18 is of such length that when properly positioned in the standard B its upper end portion will project above the upper end of the standard B and above the bearing assembly 20 seated thereon. The worm gear 19 is then screwed into the upper end of the sleeve C to a seated position 15 on the bearing 20; the gear being advanced over the upper end portion of the tubular shaft 18 and after being disposed in its operative seated position on the bearing 20 is affixed to the shaft 18 as by a means of a key 36 as particularly shown 20 in Fig. 4.

The outer sleeve D is then put in place by passing it downwardly over the upper end of the sleeve C with the keys 33 on the latter engaging the internal key-ways 34 on the sleeve D. When the 30 sleeve D is disposed in its lowermost position relative to the sleeve C the upper end portion thereof will project above the upper end of the sleeve C. The bearing assembly 31 is then put in place to seat on the upper end of the sleeve C whereupon 35 the worm gear 30 is screwed into place interiorly of the sleeve D, the upper end of which is then opened to receive the gear 30. The square shaft 29 is then passed downwardly through the gear 30 and disposed with its lower end extending into the 40 rectangular bore of the tubular shaft 18 in slideable engagement with the latter. The gear 30 is then affixed to the shaft 29 by means of a set screw 37 as particularly shown in Fig. 2. The cap 35 is then put in place to cover the open upper end 45 of the outer sleeve D. The shaft 23 with its associated beveled gear 32 is put in place at any convenient time to afford a driving connection with the gear 21.

It will be noted that when the jack is assembled as above described the parts will be relatively disposed as shown in Fig. 1, that is with the standard B encompassed by the sleeve C and the latter encompassed by the sleeve D whereby the latter will afford a housing completely enclosing the 50 inner telescoping sections of the jack thus protecting the wearing surfaces of the threads and worm gears against the deposit of dirt or grit thereon. This arrangement also provides a telescopic arrangement whereby the lowermost section is outermost and overlying an intermediate section, which is advantageous in that the structure is rendered water shedding when exposed to the weather so that rain will not reach the interior surfaces of the jack. Furthermore, the screw 55 threaded surfaces are completely concealed at all times irrespective of the relative positions of the telescopic sections so that oil or grease on such threads will not be exposed to the exterior of the jack thus enabling maintaining the outer surface 60 of the jack free of such oil or grease and whereby the jack is rendered especially applicable for use where cleanliness is a desideratum.

In the application of the invention, the outer sleeve D may be attached in any suitable manner 75 to the structure to be raised and lowered relative

to the base A, and in some instances the upper end of the sleeve D may be arranged to abut against the underside of a structure to be raised and lowered.

However, the outer sleeve D may be equipped 5 with an adjustable engaging member E as shown in Figs. 10 and 11, which embodies an annulus 38 slidably encircling the sleeve D and adapted to be engaged with the latter at various points throughout the length thereof as by means of teeth 39 10 formed on the sleeve D arranged in a row extending longitudinally of the latter and which teeth are adapted to be engaged by a tooth 40 formed on the inner periphery of the ring 38. An engaging bracket 41 projects outwardly from the periphery 15 of the ring 38 for effecting engagement with the structure to be raised and lowered by the jack. This arrangement admits of engagement by the jack of a structure extending close to and spaced slightly above the base A. 20

In the operation of the invention, assuming the parts of the jack to be disposed in the collapsed position shown in Fig. 1, rotation of the tubular shaft 18 in a clock-wise direction will act through the worm gear 19 to effect upward movement of the 25 sleeve C by reason of the latter being held against rotation by the keys 27 engaging the key-ways 28 on the standard B so as to cause the internal threads 26 on the sleeve C to advance on the worm gear 19. On thus rotating the tubular shaft 18 30 the shaft 29 is revolved therewith thereby rotating the gear 30 so that the latter will effect elevation of the sleeve D relative to the sleeve C; the keys 33 on the sleeve C engaging the key-ways 34 35 on the sleeve C to hold the latter against rotation whereby the internal screw threads 32 on the sleeve D are advanced by the gear 30. Upward movement of the sleeve C effects elevation of the worm gear 30 therewith and accordingly causes the square shaft 29 to move upwardly relative to 40 the driven tubular shaft 18 which later rotates in the standard B. This elevation of the gear 30 of itself effects upward movement of the outer sleeve D, which movement is accelerated by the lifting of the sleeve under the screw action of the gear 30 45 thereon, thus resulting in a compounded movement of the upper section of the jack.

Manifestly on having expanded the jack in effecting elevation of the sleeve D, reverse rotation of the shaft 18 will act to lower the sections C and D with the section D moving down at a speed exceeding the downward movement of the inner sleeve C.

While I have shown and described the jack as embodying a pair of telescoping sleeves C and D, 55 it manifestly may be constructed with additional of such telescoping sleeves. To this end the square shaft 29 is tubular thereby adapting it to receive a smaller square shaft of a succeeding 60 jack section when it is desired to increase the number of the sections from that here shown. It will be understood that in so increasing the jack sections the upper section will be arranged to overlie the adjacent section therebeneath. Various other changes in the construction and arrangement of the parts may be employed as fall 65 within the scope of the appended claims, and accordingly the invention embraces such changes.

I claim:

1. In a compound jack, a standard, an inner sleeve slidably telescoping said standard, having internal screw threads, a tubular shaft extending longitudinally through said standard, a worm gear on said shaft meshing with the threads on 70 75

5 said sleeve, a splined connection between said sleeve and standard, an outer sleeve encircling said inner sleeve having internal screw threads, a shaft engaged by said tubular shaft and slide-
able longitudinally therein, a worm gear on said last named shaft meshing with the threads on
10 said outer sleeve, and a splined connection between said sleeves; said outer sleeve being ar-
ranged to encompass the inner sleeve, and the latter being arranged to encompass said standard.

15 2. In a jack, a tubular standard, a tubular shaft revolvably carried in said standard, a worm gear fixed on said shaft above said standard, an internally threaded inner sleeve encompassing said standard and meshing with said gear, a splined connection between said sleeve and stand-
ard including a key carried by said sleeve and a key-way on said standard engaged by said key, an internally threaded outer sleeve encompassing
20 said inner sleeve, a splined connection between said sleeves, a worm gear meshing with the threads on said outer sleeve, and a shaft on which said last named gear is fixed extending into said tubular shaft in longitudinal slideable relation thereto and turn-
able therewith.

25 3. In a jack, a tubular standard, a tubular shaft revolvably carried in said standard, a worm gear fixed on said shaft above said standard, an

internally threaded inner sleeve encompassing said standard and meshing with said gear, a splined connection between said sleeve and stand-
ard including a key carried by said sleeve and a key-way on said standard engaged by said key, 5 an internally threaded outer sleeve encompassing said inner sleeve, a splined connection between said sleeves, including key-ways formed interior-
ly of said outer sleeve and keys on said inner sleeve slidably engaging said key-ways, a worm 10 gear meshing with the threads on said outer sleeve, and a shaft on which said last named gear is fixed extending into said tubular shaft in longitudinal slideable relation thereto and turn-
able therewith.

15 4. In a compound jack, a standard, a plurality of internally threaded sleeves slidably encompassing said standard with adjacent sleeves telescoping each other progressively outward from said standard so that the lower ends of the outer-
most sleeve will overlie the adjacent inner sleeve, means for holding said sleeves against rotation relative to each other and to said standard, worm gears engaging the threads of each of said sleeves, and means for collectively rotating said 20 25 worm gears to advance and retract said sleeves thereon.

CECIL F. DAVEY.
